US00D546458S

(12) **United States Design Patent** (10) **Patent No.:** **US D546,458 S**
Hannant (45) **Date of Patent:** **** Jul. 10, 2007**

(54) **BLOOD GLUCOSE METER**

(75) Inventor: **Matthew Hannant**, London (GB)

(73) Assignee: **Hypoguard Limited**, Woodbridge (GB)

(**) Term: **14 Years**

(21) Appl. No.: **29/231,865**

(22) Filed: **Jun. 10, 2005**

(51) **LOC (8) Cl.** **24-01**

(52) **U.S. Cl.** **D24/186**

(58) **Field of Classification Search** **D24/169, D24/183-187, 216-234; 422/56, 58, 61, 422/67, 68.1, 102, 104; 436/46, 50, 55; 600/309, 600/318, 322, 368, 583; D10/81, 104**

(57) **CLAIM**

The ornamental design for a blood glucose meter, as shown and described.

DESCRIPTION

FIG. 1 is a top plan view of a blood glucose meter showing the new design.

FIG. 2 is a left side elevation view of the blood glucose meter.

FIG. 3 is a front elevation view of the blood glucose meter.

FIG. 4 is a rear elevation view of the blood glucose meter.

FIG. 5 is a bottom plan view of the blood glucose meter.

FIG. 6 is a right side elevation view of the blood glucose meter; and,

FIG. 7 is a perspective view of the blood glucose meter.
